GRINDING OR POLISHING MACHINE

Charles E. Evans, Aurora, Ill.

Application April 18, 1932, Serial No. 605,907

3 Claims. (Cl. 51—129)

This invention relates to a machine for grinding or polishing surfaces, and has for its main object to provide an improved machine of this character for performing these operations on various types of lenses, particularly spectacle lenses, and also on mirrors, reflectors, etc. Another object of my invention is to provide an improved machine of this character especially adapted for grinding or polishing spectacle lenses whose surfaces are not truly spherical, such as lenses shown and described in my co-pending application Serial No. 579,451, after the surfaces of such lenses have been shaped to the desired form by a previous grinding operation. A further object of my invention is to provide an improved grinding or polishing member which will readily adapt itself to the surfaces of lenses of curvatures different from that of said member, itself, and which is capable of imparting substantially uniform pressure over the lens surface while the latter is being operated upon. The invention consists in certain features and elements of construction, in combination, as herein shown and described, and as indicated by the claims.

In the drawing:

Figures 1 and 2 are side elevation and plan views respectively of an elementary form of grinding or polishing machine embodying my invention.

Figure 3 is a section through a modified form of grinding or polishing member.

Figure 4 shows a further modification of grinding or polishing member.

For purposes of illustration I have chosen to embody my invention in a very elementary form, as may be seen in the drawing. Supported on the bench, A, or other suitable standard, is a vertically disposed drive shaft, B, journaled at its lower end in a bearing, C, and at its upper end in a thrust bearing, D. Rigidly secured to the lower end of the shaft, B, immediately above the bearing, C, is a drive wheel or pulley, E, around which is trained a flexible belt, F, which may be understood to be connected to a suitable source of power, (not shown). Rigidly secured to the upper end of the shaft, B, is a cup-shaped support, G, which is formed at its bottom with a hub portion, G¹, supported on the upper end of the end thrust bearing, D. Secured in this cup-shaped support in any suitable manner is my improved grinding or polishing member, H, which in Figure 1 of the drawing is shown as of hollow spherical form, and which may be understood to contain fluid, that is, either gas or liquid; the outer surface of the spherical member, H,

being formed of flexible material such as rubber so as to render the surface of said member flexible and resilient.

If desired this grinding or polishing member may be of modified form, as indicated at H¹, in Figure 3. In this construction the member is formed of a mass of resilient material such as sponge rubber, which meets the requirement of a suitable support for a flexible and resilient surface.

Secured on the upper portion of said spherical grinding or polishing member, H, in any suitable manner, as by adhesives, is a piece of material, I, such as felt or other suitable substance. It is the outer surface of this piece of fabric, I, which is the effective grinding or polishing surface, when supplied with the necessary grinding or polishing compounds, such as rouge. If desired this fabric may be anchored in place on the member, H, by lacing it to the support, G.

Mounted on the top of the bench, A, adjacent said grinding element is a bracket, J, to which is connected for universal movement a hand lever, L. The universal connection between the hand lever and the bracket consists of a horizontally extending pin, K, to the inner end of which the lever, L, is pivotally attached by means of a transverse, horizontal pivot pin, K¹. As may be seen in the drawing the lever, L, may be rotated about the horizontal axis of the pin, K, which is substantially in alignment with the center of curvature of the outer surface of the grinding or polishing member, H; the purpose of this arrangement will hereinafter be made apparent.

Adjustably threaded through a boss of the lever, L, in substantially radial relation to the member, H, is a spindle, M, the lower end of which projects into a socket formed in the top of the member, P, which is similar to what is commercially known as a "blocking body" and which is in fact the carrier for the lens indicated at Q. It is to be understood that the lens, Q, is adhesively secured to the carrier, P, by any suitable known method.

It may be understood that the lens, Q, shown in the drawing, has a concave surface in contact with the grinding or polishing surface of the member, H. In the normal operation of a machine of this character the shaft, B, rotates counter-clockwise, and the hand lever, L, is pressed toward the member, H, and because of the flexible and resilient surface of said grinding or polishing member, H, said member will impart substantially uniform pressure to the surface of the lens, Q, that is being operated upon.

By the pressure applied through the lever, L, causing the lens to frictionally engage the rotating surface of the member, H, said lens and the carrier or block, P, will spin about the end 5 of the spindle, M, and by rocking the lever, L, back and forth about the axis of the pin, K, the surface of the lens will be ground or polished. The relation of the axis of the pin, K, to the center of the member, H, permits moving the 10 lens over the surface of the member, H, in a true spherical arc. When the lever, L, is positioned with the lens, Q, substantially centered on the member, H, said lens will tend to spin about the end of its spindle, M, at approximately the same 15 rate of speed as the surface speed of that part of said member, H, which is engaged thereby. And when said lever is shifted sidewise, the difference in frictional pressures on different areas of the lens will cause the lens to spin at a variable speed resulting in slippage between the 20 surface of the lens and the surface of the member, H, thus positively causing grinding or polishing of the lens surface. To insure against any possibility of the carrier and the lens being 25 accidentally disengaged from the spindle resulting in danger of injury to the operator, as well as breakage of the lens, the socket for the end of the spindle, M, in the carrier block, P, is made quite deep.

Because of the flexibility of the surface of the 30 grinding or polishing element, H, with which the lens is pressed into contact, and the relation of the point of the spindle, M, to this surface, there is a tendency of the forward edge of the lens to bite into the surface of the grinding or 35 polishing member, particularly when the lens is rocked to the right side of the vertical center, and for overcoming this difficulty the lever, L, is formed with a pair of lugs, R, in which is journaled a roller, S, which may be understood to be 40 mounted on anti-friction bearings. This roller is dimensioned and positioned to come in contact with the upper flanged surface of the lens carrier, P, and is adapted to exert pressure at the 45 rear edge of said block, so that the forward edge of the lens will be held from too severe engagement with the surface of the grinding or polishing element, H.

By virtue of the construction embodied in my 50 novel grinding and polishing element, it will be apparent that such a member is adapted to be used for grinding or polishing the surfaces of lenses having quite a wide range of curvatures, 55 preferably curvatures whose radii are greater than the normal radius of curvature of said member. It will also be seen that such a grinding or polishing member may be conveniently employed for grinding or polishing the surface of a lens having a truly spherical curvature. It 60 is also manifest that my improved polishing member, H, having a flexible and resilient surface readily adapts itself advantageously for use with certain commercial methods wherein it is desirable to grind or polish a number of lenses 65 at one time; such as where several lenses are supported on a common "blocking body" for engagement with a single grinding or polishing member which is of proper shape and size. It may be equally adaptable to a method wherein 70 several lenses are secured to the inner wall of a cup shaped member and the surfaces of said lenses engaged by a common lap block. In the latter method it is to be understood that the cup member and the lap block have imparted there- 75 to proper relative motions for obtaining the de-

sired grinding and polishing action on the surfaces of the lenses. For such use the lap block, which desirably embodies my improved construction consisting of a resilient and flexible surface, may be formed with a radius of curvature greater than the curvature of the surfaces of said lenses that are being operated upon.

Figure 4 of the drawing shows a further modification of my grinding or polishing member; in this construction the cup shaped support, U, is somewhat flatter than the support shown in Figure 1 and is formed with a vertical marginal wall, U¹. A flexible diaphragm, V, is stretched over the upper edges of said vertical wall, U¹, of the support and has its marginal edges rigidly secured to the wall, U¹, by an encompassing band, W. The bottom wall of the cup-shaped support, U, is formed with a nipple, Y, which may be understood to be provided with the usual check valve for admitting gas into the sealed chamber formed by the cup support, U, and the diaphragm, V. By the use of such a valve it will be obvious that the pressure within the container may be varied as desired but preferably it is sufficient to cause the diaphragm to bulge outwardly, producing a convexly curved resilient surface, as seen in the drawing. It may be understood that the flexible diaphragm may be formed of a material whose characteristics are such as permit it to serve as the effective grinding or polishing surface, or a piece of felt or other suitable material may be secured thereto in the usual way. A grinding or polishing element of this character provides a substantially flat grinding or polishing surface which is particularly well adapted for use in grinding or polishing the convex surface of a lens. Under certain conditions it may be desirable to have the diaphragm, V, stretched straight across the bowl, U, with the pressure in the bowl at substantially atmospheric pressure, or perhaps by reducing the pressure in the bowl the diaphragm may be drawn downwardly to present a concave working surface.

Although I have shown and described an elementary embodiment of my invention, it is manifest that it is capable of modification and rearrangement without departing from the spirit and scope thereof. I do not therefore wish to be understood as limiting myself to the particular construction herein shown and described, except as indicated by the appended claims.

I claim:

1. In a lens grinding or polishing machine including a rotary support, a grinding or polishing member carried by said support, said member having a curved resilient wall portion, adapted for conforming to the surface of a lens of different curvature, a hinged support, a lens block associated with said support and arranged to accommodate itself to a substantial range of universal movement, said hinged connection of the support permitting disposing a lens in proper relation to said member, and permitting oscillation of the lens back-and-forth over said resilient grinding or polishing surface of the member, and means carried on said support and engageable with one edge of the block for rocking the opposite edge of the lens outwardly with respect to said member.
2. In a lens grinding or polishing machine including a rotary support, a grinding or polishing member carried by said support, said member having a curved resilient wall portion, adapted

for conforming to the surface of a lens of different curvature, a hinged support, and a lens block associated with said support and arranged to accommodate itself to a substantial range of universal movement, said hinged connection of the support permitting disposing a lens in proper relation to said member, and permitting oscillation of the lens back-and-forth over said resilient grinding or polishing surface of the member, the axis of the hinged connection of the support which permits said back-and-forth oscillation, being approximately in alignment with the cen-

ter about which said curved surface of the grinding and polishing member is generated.

3. In a grinding or polishing machine of the character described, a hinged support, a lens block associated with said support and arranged to accommodate itself to a substantial range of universal movement for permitting the lens to accommodate itself in proper relation to the grinding or polishing member, and means for limiting the movement of the lens block in cer-
